SAND CUTTING MACHINE

Filed July 17, 1923

FIG. 1

FIG. 2

FIG. 4

INVENTOR.
ELMER E. DAVIS.

BY *Lockwood Lockwood*.

ATTORNEYS.

UNITED STATES PATENT OFFICE.

ELMER E. DAVIS, OF MUNCIE, INDIANA.

SAND-CUTTING MACHINE.

Application filed July 17, 1923. Serial No. 652,054.

To all whom it may concern:

Be it known that I, ELMER E. DAVIS, a citizen of the United States, and a resident of Muncie, county of Delaware, and State of Indiana, have invented certain new and useful Sand-Cutting Machines; and I do hereby declare that the following is a full, clear, and exact description thereof, reference being had to the accompanying drawings, in which like numerals refer to like parts.

This invention relates to a sand cutting machine of the general character disclosed in the copending application, Serial No. 15 517,735, filed November 25, 1921.

The chief object of this invention is to improve the construction of a machine so that it will separate cores, reenforcing wires, vent stems and the like from the sand utilized in molding and retain the same until such time as it is desired to remove them from the machine.

The chief feature of the invention consists in the accomplishment of the foregoing object.

Another feature of the invention is the provision of means associated with the trap which permits the cores, reenforcing wires, vent stems and the like to be removed from the trap.

The full nature of the invention will be understood from the accompanying drawings and the following description and claims.

In the drawings Fig. 1 is a side elevational view of the sand cutting machine, including the invention. Fig. 2 is an enlarged longitudinal sectional view of the invention. Fig. 3 is an end view of the invention taken along the line 3—3 of Fig. 2 and in the direction of the arrows. Fig. 4 is a transverse sectional view taken along the line 4—4 of Fig. 2 and in the direction of the arrows.

In the drawings there is illustrated a machine of the general character described in the copending application referred to. Herein such a machine consists of a framework 10 which supports a chute 11 supplied by a conveyor or elevator construction 12, operated by a motor 13 carried by the frame 10. Journaled in the inclined bearings 14 and 15, the latter being the lower bearing, is a shaft 16, which upon one end carries a bevel pinion 17 meshing with the bevel gear 18 driven by the motor 13.

The shaft 16 carries a pair of hubs 19 and 20, which support the spiders 21 and 22 respectively. The spiders include the circular bands 23 and 24 respectively, and these bands support a cylindrical, mesh riddle 25. The upper end of the mesh riddle is defined by the annular member 26, and this as shown provides an open mouth into which the chute 11 discharges. Also supported by the annular band 23 is a baffle construction having a flanged portion 27 with a central opening 28 and a peripheral portion 29 by which it is secured to and supported by the band 23. Supported by the baffle 27 is a cylindrical shell 30 which is perforated as at 31. The other or free end of the shell is closed by a circular plate 32, which plate 32 has an opening 33 therein. The opening 33 is closed by a closure or door 34 hingedly supported at 35 and latched as at 36.

The operation is as follows: The molding sand including the cores, reenforcing wires, vent stems and the like is taken from the pile 50 by the elevator construction 12 and discharged thereby into the chute 11, which in turn discharges into the open mouth of the riddle 25. The riddle 25 is rotated through the shaft 16, and to prevent longitudinal movement of the shaft, a collar 37 is secured thereto, which bears upon the lower bearing 15. Rotation of the riddle 25 carries with it the trap construction which forms the closed lower end of said riddle. In the rotation of said riddle, the molding sand is screened and is discharged beneath the riddle, the larger particles working their way toward the band 23. These particles, and chiefly the cores, reenforcing wires, vent stems and the like in the rotation of said riddle work their way upwardly adjacent the plate 27 and pass said baffle through the opening 28 and discharge into the trap formed by the end plate 32 and the cylinder 30. The loose sand carried by said cores, reenforcing wires, vent stems and the like in the continued rotation of the riddle discharges through the apertures 31 and is again utilized. The machine is operated until either the trap becomes filled with cores, reenforcing wires, vent stems and the like, or until all of the molding sand has been worked open. Then the machine is stopped, the door 34 opened, and said cores, reenforcing wires, vent stems and the like re-

removed from the trap. This construction not only separates the relatively heavy cores, reenforcing wires, vent stems and the like from the sand, but also removes the same from the riddle, which is of mesh construction and is less adapted to continuously support a heavy revolving load than the shell 30. Thus, there is less opportunity for the breaking of the riddle and the life thereof is thereby increased.

10 The invention claimed is:

1. In a sanding machine for foundries and the like, the combination of an inclined shaft, a spider supported thereby, a peripherally perforated shell concentric with the shaft and supported at its upper end by the spider, means closing the lower end of said shell, a cylindrical screen supported at its lower end by said spider communicating with said shell, whereby the screen is closed by said shell and shell closure, and a peripheral baffle between said shell and said screen and supported by said spider.

2. In a sanding machine for foundries

and the like, the combination of an inclined shaft, a spider supported thereby, a peripherally perforated shell concentric with the shaft, means closing the lower end of said shell, a cylindrical screen supported by said spider and associated with said shell, whereby the screen is closed by said shell and shell closure, and normally closed means for permitting access to said shell.

3. In a sanding machine for foundries and the like, the combination of an inclined shaft, a spider supported thereby, a peripherally perforated shell concentric with the shaft, means closing the lower end of said shell, a cylindrical screen supported by said spider and associated with said shell, whereby the screen is closed by said shell and shell closure, a baffle between said shell and said screen, and normally closed means for permitting access to said shell.
